UNITED STATES PATENT OFFICE.

LUCIUS S. EDLEBLUTE, OF CINCINNATI, OHIO, ASSIGNOR OF TWO-THIRDS
TO RUFUS P. WHITE AND HORACE W. SMITH, BOTH OF SAME PLACE.

TRACE-FASTENING FOR SINGLE-TREES.

SPECIFICATION forming part of Letters Patent No. 254,293, dated February 28, 1882.

Application filed January 28, 1881. (No model.)

To all whom it may concern:

Be it known that I, LUCIUS S. EDLEBLUTE, of the city of Cincinnati, in the county of Hamilton and State of Ohio, have invented certain new and useful Improvements in Trace-Fastenings for Single-Trees, of which the following is a specification.

My invention relates to that class of fastenings in which a bolt or equivalent device attached to the end of the single-tree is used for the purpose of securing the trace thereto, the objects of my improvements being to provide a bolt-fastening which, being simple in design, secures cheapness of construction and ease in the attaching and detaching of its various parts to the single-tree.

Figure 1 is a perspective view of the invention shown attached to the end of a single-tree with a trace fastened to same. Fig. 2 is a sectional elevation of the same. Fig. 3 is a detached perspective view of the bolt shown in Figs. 1 and 2. Fig. 4 is a sectional elevation of a modification of the invention applicable also to neck-yokes. Fig. 5 is a detached perspective view of the bolt shown in Fig. 4. Fig. 6 is a perspective view of the end of a trace, showing the preferred form of making the same.

Similar letters refer to similar parts in all figures of the drawings.

A is the end of a single-tree, to which is attached the tube or casing B, holding the operating parts. This tube or casing B is provided with two ears or straps, one of which, C, is shown in Figs. 1 and 4, by which it is fastened to the end A of the single-tree either by a bolt or by any other suitable device. The bolt D has a shank, m, and is provided with a suitable thumb-piece, d, for operating the same, and is so constructed as to drop readily into place through the slot b in the casing B. This thumb-piece d is located some distance behind the shank m, and is connected to the latter by the plate n, which latter also serves to cover the slot in the casing through which the bolt-rod d' and shank m have been introduced. The bolt-rod d' works freely through the aperture b' into the socket e of the lip or guard E, and when in use passes through the hole

provided in the trace for holding the same. 50 The bolt D is also provided with a lug or projection, d², passing through the slot b' of the casing B, to which may be fastened a strap or line of any kind by means of a ring, as shown, or by any other suitable device, in order to 55 operate the bolt from the seat of the vehicle or from any desired distance. The bolt D is held firmly to its place by the spiral spring F, working against the piston G at the rear end of the bolt, and said spring is secured from slipping by fitting into the recess or cup g of the piston G. The bolt D is made with a projection or rivet, d³, to fit into a corresponding hole in the piston G, the shank m and rod d' being first dropped into place in the casing B. 65 The piston G is then introduced through the rear end of the casing and riveted to the bolt D by means of the aforesaid projection or rivet d³, as fully shown in Fig. 2. In the modified form shown in Figs. 4 and 5 this method of 70 fastening is dispensed with, and the piston G is made with and a part of the bolt D, being made small enough to permit of the bolt being dropped into place through the slot b of the casing B.

The end A of the single-tree is provided with longitudinal slots a a, Fig. 1, at right angles to each other. This end is made slightly larger than the interior of the casing B, and is driven into the same, the slots a a giving spring enough 80 to the wood to permit it to enter, and at the same time causing it to expand slightly when in place, and by binding upon the sides of the casing furnish an additional mode of fastening. The end A having been previously 85 bored for the reception of the tube or bushing H, into which the spring F works, and the bushing being inserted therein, as shown, the construction of the end of the single-tree, when driven into the casing B, serves to bind and 90 secure this bushing in place. This bushing is made of sufficient strength to resist any action caused by shrinkage of the wood, and, being made of sufficient size, affords a perfectly safe protection to the spring F, permitting it to act freely and without any restraint 95 whatever. The end of the single-tree is cut off at such a place as will give sufficient room in

the interior of the casing B for the retraction of the bolt D, permitting it to fully clear the space between the lip E and the end of the casing when said bolt is drawn back to permit of the insertion or removal of the end of the trace.

In the modified form as shown in Figs. 4 and 5, the bolt and piston are made in one piece, as heretofore described, with the exception that the thumb-piece d is made separate, 10 and is pivoted to the body of the bolt by the pivot d⁴, as shown in the drawings, the object being to allow the thumb-piece d to be used as a latch or catch by being swung into the position shown by the dotted lines in Fig. 4, after 15 the strap or trace has been secured by the bolt D. The lug or projection d² not being used in the modified form, the slot b' in the casing B is dispensed with. The object of this modified form is to show a method of fastening applicable to neck-yokes as well as to single-trees.

A preferred method of making the end of the trace or strap to be used in connection with this invention is to fasten in the same an eyelet, I, of any approved form, having a hole, i, 25 of sufficient size to permit the passage of the shaft of the bolt.

The mode of operation of my invention is as follows: When it is desired to fasten or unfasten the trace the bolt D is pulled back by 30 means of the thumb-piece d or a strap attached to the lug d² until the end of the rod d' fully clears the space between the lip E and the end of the casing B. The end of the trace is then placed in this space in such manner that the 35 hole i in the trace or strap is directly opposite the end of the rod d'. The hold is then released upon the thumb-piece d, and the spring F forces the shaft d' through the hole i into socket e, being the position shown in the drawings.

40 The end of the rod d' is preferably beveled off on the top and bottom, and these beveled edges operate after the manner of a beveled

door-latch, so that when the trace is introduced between the lip and end of the casing, and the rod d' is partially retracted, and the edge 45 of the trace is pressed against the rod d', the bevels aid in retracting the rod d' and facilitate the introduction of the trace into a position where the rod d' can enter the hole i there- 50 of.

What I claim as new and of my invention, and desire to secure by Letters Patent, is—

1. In a trace and yoke fastening device, the bolt d', attached to one side of the shank m, said shank having the piston G riveted to its opposite side, and being provided with plate n and thumb-piece d, in combination with the casing B, single-tree A, and spring F, substantially as and for the purposes specified.

2. The combination of the single-tree A, casing B, and fastening device D, constructed substantially as described, and provided with cup or piston G, spring F, and bushing H, substantially as described.

3. In a trace-fastening device, the shank m, 65 provided with thumb-piece d and bolt d' and projection d² and piston G, in combination with the single-tree A, casing B, and bushing H, substantially as and for the purposes specified.

4. In a trace and yoke fastening device, the 70 combination of a suitable bolt and devices for retracting the same, and the spring F, bushing H, single-tree A, and casing B, substantially as described.

5. A sliding spring-bolt consisting of the 75 shank m, provided with plate n and thumb-piece d and the bolt d' and piston G, said bolt being actuated by a suitable spring, substantially as described.

LUCIUS S. EDLEBLUTE.
